UNITED STATES PATENT OFFICE

149,238

DESIGN FOR AN ARTIFICIAL FISH LURE

Eugene P. Vaars, Dayton, Ohio, assignor to
Electronic Units Inc., Dayton, Ohio, a corpora-
tion of Ohio

Application February 16, 1946, Serial No. 126,626

Term of patent 14 years

(Cl. D31—4)

To all whom it may concern:

Be it known that I, Eugene P. Vaars, a citizen of the United States, residing at Rural Route No. 4, Dayton, in the county of Montgomery and State of Ohio, have invented a new, original, and ornamental Design for an Artificial Fish Lure, of which the following is a specification, reference being had to the accompanying drawing, forming part thereof.

Fig. 1 is a top plan view of an artificial fish lure illustrating my new design.

Fig. 2 is a side elevational view thereof.

Fig. 3 is a bottom view of my new design.

Fig. 4 is a front view thereof.

Fig. 5 is a rear view thereof.

My new design is characterized by a substantially tear drop shaped body having a combined fin and tail portion extending horizontally from the mid-section of the body, and a vertical fin extending from the mid-section of the lower part

of the body from a point about half way between the center and the front of the body and extending past the rear end thereof and intersecting the horizontal fin near the rear portion thereof and also extending over the rear top portion of the body at the mid-section thereof, all as shown.

I claim:

The ornamental design for an artificial fish lure, as shown and described.

EUGENE P. VAARS.
